UNITED STATES PATENT OFFICE.

WILLIAM J. NEIDIG, OF MADISON, WISCONSIN, ASSIGNOR TO NEIDIG TYPEWRITER CO.,
OF CHICAGO, ILLINOIS, A CORPORATION OF ILLINOIS.

TYPE-WRITING MACHINE.

1,114,795.

Specification of Letters Patent. Patented Oct. 27, 1914.

Application filed December 9, 1912. Serial No. 735,643.

To all whom it may concern:

Be it known that I, WILLIAM J. NEIDIG, a citizen of the United States, residing at Madison, in the county of Dane, State of 5 Wisconsin, have invented a certain new and useful Improvement in Type-Writing Machines, of which the following is a specification, reference being had therein to the accompanying drawings.

10 Certain principles and features of my invention as described herein are included within my generic invention which is described and claimed in Letters Patent No. 1,087,045, granted February 10, 1914, upon 15 my application dated April 30, 1909, Serial No. 493,193.

My general invention supplies the operator of a typewriting machine with purely automatic means, under the novel control of 20 a typewriter-mechanism part used in the operation of typewriting, whereby without exercising preliminary care he is able to inform himself of the position of his advancing sheet, so that he may know at any time 25 the extent of the matter completed on his sheet and therefore the extent of the uncompleted portion of his sheet. It also supplies him with automatic means under the control of a typewriter-mechanism part whereby 30 such types as may be desired of visual, audible and machine-lock signaling devices may be employed to indicate the arrival of the sheet into predetermined position.

The present branch or division of the invention has as one of its special features the 35 novel use of the feed-roll release or paper-gage-operating mechanism, that is to say the sheet-positioning mechanism, in the typewriting machine, for the control of indicating means.

In the embodiments of the invention represented in the drawings, the types of indicating means shown as so controlled comprise indices, a visual signaling means, an audible 45 signaling means, and a means for locking the printing instrumentalities against use in printing.

Other features consist in certain novel combinations of operating elements characterized by either the general or the specific controlling agencies named.

Other features will be as hereinafter explained.

The said features are intended for use as

may be found desirable in connection with 55 sheet-position-indicating mechanisms of the general character specified, under the varying conditions of service.

In the drawings,—Figure 1 is an end elevation, partly broken away and in section, 60 of portions of a typewriting machine showing my invention as applied thereto. Fig. 2 is a plan view of portions of the same, but with the platen arbor removed. Fig. 3 is a cross-section of portions of Fig. 1 on the 65 line 3—3. Figs. 4 and 5 represent alternative arrangements of indices. Fig. 6 is an end elevation of a portion of another embodiment of my invention, partly in section and with the platen-frame removed, indicating another arrangement of gearing. Fig. 7 is a cross-section of portions of the same on the line 7—7.

For the purpose of more clearly explaining my invention, the following typewriter-mechanism parts are described: The main frame of a typewriting machine, indicated in the drawings at 1, bears the usual transversely movable carriage 2, upon which is mounted the usual vertically shifting platen-frame indicated at 3. Said platen-frame has journaled therein in approved manner a platen arbor 4 bearing fixedly attached thereon a platen 5. The platen as herein regarded is the principal feed-roll for advancing the sheet through the machine, and it is rotated as in practice by typewriter-mechanism parts not necessary to be shown 75 herein. Fixedly attached on platen-frame 3 is a transversely extending cross-piece 7 bearing pins 8 upon which are journaled arms 9, only one of said pins and arms being shown in Fig. 1 but the others lying behind and in line with the one shown and having the same end elevation, as will be readily 80 understood. Said arms have journaled in the swinging ends thereof feed-roll arbor 10 bearing feed-roll 11. Springs 12 fixedly attached upon the under side of arms 9 engage at the free ends upon lugs 13 on piece 7 85 so as to tend to press arms 9 and feed-roll 11 toward the platen. A laterally extending rock-shaft 14 has its ends journaled in the ends of platen-frame 3 and has fixedly attached thereon an upstanding lever 28 for 90 the manual rocking of the shaft. Said shaft bears also a plurality of fixedly attached arms 15 bearing near the free ends thereof

100 the manual rocking of the shaft. Said shaft bears also a plurality of fixedly attached arms 15 bearing near the free ends thereof

the upstanding paper-gages or paper-stops 16, feed-roll 11 lying between said arms. Also fixedly attached upon said rock-shaft are the short lever-arms 17, suitably positioned laterally to engage upon arms 9. When lever 28 is pressed rearwardly, arms 17 bear against arms 9 and lift feed-roll 11 away from the platen against the pressure of springs 12. At the same time arms 15 are elevated until paper-gages 16 meet the platen surface. The purpose of the roll-release provision as regarded herein is to assist in positioning the leading end of the sheet, and the paper-gage provision is a co-operating provision having the same purpose. It will be understood by those skilled in the art that some styles of typewriting machines do not employ paper-gages for this purpose. The usual paper-table for the 20 port of the entering sheet is indicated at 69 (Fig. 1). Usual type-bars, indicated at 70, are mounted on the main frame in well-known manner, bearing printing types 71, the same having actuation against the sheet 25 from key-levers indicated at 72. Other typewriter-mechanism parts are as in practice. The typewriter structure described is old; it is or may be of any approved form.

As applied to the above structure, the 30 embodiment of my invention more particularly illustrated in Figs. 1 to 3 in the drawings is described thus: Attached on platen arbor 4 against the end of platen 5 so as to rotate in unison therewith is toothed 35 driver 18, said driver here conveniently serving also as the usual platen head. Journaled loosely on arbor 4 so as to be revolute independently of the platen is operative member 6, said member in this case 40 having the form of an index-carrier or index-bearing drum supported from an attached central bushing by a rear wall or web and having a central aperture in the face wall thereof. A laterally extending 45 split post 19 on platen-frame 3 projects through said aperture into the drum. An expanding severed ring 20 of suitable resilience bears frictionally against the inner surface of the crown of the drum so as to 50 slip thereon. Upon said ring is attached one end of a helical spring 25, the other end of which is held in the cleft of said split post, said spring tending to rotate said drum backwardly. The purpose of the friction-ring is to prevent over-winding the 55 spring. The face wall of drum 6 is supplied with a series of threaded holes 22, into any one of which may be screwed a projection 23, and with a second series of 60 holes radially exterior with respect to the first series, into any one of which may be screwed a projection 26. Pin 27 on platen-frame 3 has journaled thereon a stop 25', said stop tending by gravity to rest against 65 pin 29 on said platen-frame and having an

inwardly extending portion 30 which lies in the path of said projection 26 when the stop is in its normal position. Projection 26 can be moved past stop 25' forwardly, the stop separating from pin 29 in such an action, but not backwardly. The provision permits drum 6 to be rotated forwardly to the extent of more than one revolution. The purpose of spring 25 and stop 25' is to give the drum a suitable constant starting or initial position, the drum being rotated backwardly by said spring until projection 26 thereon is detained by said stop. I give said drum a working movement coördinate with that of the sheet from the said initial position, preferably by connecting it with the platen. The connecting means employed is not especially material. In the embodiments illustrated in the drawings, as in Figs. 1, 2, 3, use is made of a 80 convenient arrangement of toothed gearing for the purpose, as follows: Toothed driver 18 has already been described as rotating in unison with the platen. Fixedly attached upon drum 6 is a toothed rim or 85 wheel 31. Rock-shaft 14 previously described bears fixedly attached thereon an arm 32, supplied near one end with a pin 33, on which is journaled a riding gear consisting of toothed wheel 34 and toothed 90 wheel 35 assembled to rotate as a unit, wheel 34 preferably having the greater diameter. The arrangement is such that wheel 34 is adapted to mesh with wheel 18 at the same time that wheel 35 meshes with wheel 31, 95 so that when wheel 18 is rotated wheel 31 is rotated thereby, but more slowly. Wheels 34 and 35 are normally held in mesh with wheels 18 and 31 by the action of springs 100 12, through arms 9, arms 17 and rock-shaft 14.

When the sheet is ready to be entered, roll-release lever 28 is pressed rearwardly as usual, thereby separating feed-roll 11 from the platen so as to permit the leading end of the sheet to pass between the two and into the desired starting position. In this case such action of the roll-release lever causes paper-gages 16 to be raised into the paper-path, to the end that the leading end 110 of the sheet may be positioned through the assistance of paper-gage means, as shown in Fig. 1. The rocking of shaft 14 by said roll-release lever causes wheels 34 and 35 to be moved out of mesh with wheels 18 and 31, thereby releasing drum 6 from operative connection with the platen. Spring 25 at once rotates drums 6 backwardly until projection 26 is detained by stop 25', that is to say into initial position. Both sheet 115 and drum having been positioned, lever 28 is released, and springs 12 actuate arms 9 and feed-roll 11 toward the platen, thereby through arms 17 and shaft 14 moving arm 32 toward the platen arbor and causing 120 130

wheels 34 and 35 to mesh with wheels 18 and 31. The same action moves paper-gages 16 out of the paper-path. When the sheet is now advanced by the platen into the several printing positions, drum 6 is correspondingly advanced by the platen into given indicating positions. That is to say, using the embodiment shown in Figs. 1 to 3 as an illustration, when the sheet arrives in position for the printing of the first line, the index 1 on the drum will be brought into indicating position before pointer 73, and index 2 for the second line position on the sheet, and so on to the bottom of the sheet. And if it be desired to change the position of the first line upon the sheet, pin 26 will be seated or screwed into the suitable threaded hole 24 to position the drum so that index 1 will be brought into indicating position when the new first line position on the sheet arrives at the printing point. The form, size, position, order and number of the indices on the drum or index-carrier will be as may be desired, as will the indicating unit represented. I prefer to employ familiar indices such as Arabic numerals. In the indices shown in Fig. 2 the unit of indication is the common double-spaced line unit, the order being the ascending order. It is of course not necessary that the indices come to rest always exactly opposite the pointer, nor that index 1 (say) should indicate the first line position on the sheet. Alternative arrangements of indices are shown in Figs. 4 and 5, that in Fig. 4 consisting of indices in ascending order in a series extended twice around the drum, and that in Fig. 5 of indices in descending order.

Additional indicating means are employed at will as follows: Inwardly extending pin 37 on platen frame 3 has journaled thereon an elbow-lever 38, one arm of which projects into the path of projection 23 aforesaid on drum 6, and the other arm of which bears a pin 39. Carriage-frame 2 bears a pin 40, journaled on which is a rock-piece 41. A similar pin will be understood as carried upon the other end of said carriage-frame, directly in line with the pin shown, on which is journaled a similar rock-piece. Rock-pieces 41 are connected by a laterally extending bail portion 42, with which they form a rocking bail-piece or universal connection between the laterally movable carriage and the main frame portion of the machine. Said bail-piece is connected with lever 38 by means of rod 43, journaled at one end on pin 39 before mentioned and having an elbow-slot 44 in the other end into which projects pin 45 on piece 41. Transversely extending cross-piece 47 on main frame 1 bears brackets 48, one of which is positioned about midway between the ends of the main frame. In said brackets is journaled a rock-shaft 49,

bearing fixedly attached thereon adjacent the midway bracket a lever 50 in suitable position to be engaged by bail 42 in every working position of the carriage. Arm 51, also fixedly attached upon said rock-shaft, 70 bears pin 52, upon which is journaled one end of downwardly extending rod 53. Main frame 1 has journaled therein the rock-shaft 54 having fixedly attached near either end the arms 55 connected by a transversely extending bail-rod 56. Fixedly attached arm 57 on said shaft 54 bears a pin 58 upon which the lower end of rod 53 is journaled. Rock-shaft 54 has attached thereto, preferably by means of set-screw 59, a hub 60, from 80 which extends the light spring stem 61 bearing bell-hammer 62. Bell 63 is conveniently supported in the path of said hammer by central pin 64 on frame 1. The usual key-levers 72 are supplied each with an overhang 72' in such manner that bail-rod 56 can be moved under them to lock them against actuation, but when said bail-rod is in the position shown in Fig. 1 they are not locked thereby. A contracting spring 65 attached at one end to laterally extending post 66 on frame 1 and at the other to an ear 67 on rod 53 tends to hold arm 55 against stop 68 on frame 1 and bail-rod 56 out of locking position.

The above described mechanism operates thus: At the predetermined time pin 23 engages with lever 38 and moves it upwardly, thereby through pin 39, rod 43, pin 45 and rock-piece 41 rocking bail 42 downwardly. 100 This action is communicated by said bail to arm 50, and through rock-shaft 49, arm 51, pin 52, rod 53, pin 58 and arm 57 to rock-shaft 54. Thereby through hub 60 and hammer-stem 61 bell-hammer 62 is caused to 105 strike bell 63 and give an audible signal that the sheet is in predetermined position. It will be understood that the usual abrupt starting and stopping action of the platen, transmitted through sensitive spring-stem 61 to a hammer-head having some inertia and momentum is availed of to cause the bell-stroke in this case, for reasons of convenience. The operator is now informed that his predetermined page is completed, 110 and he can remove his sheet without losing time in trying to write further upon that page. Bail 56 through arms 55 on rock-shaft 54 is by the same action moved under the overhang 72' on key-levers 72. In case 115 the audible signal is disregarded, the operator finds that he can no longer do any printing the printing instrumentalities having been locked. He thereupon runs out his sheet in usual manner, pin 23 passing out of engagement with lever 38 and allowing the parts to assume the position shown in Fig. 1. In case the operator wishes to print further upon that sheet before removing it he can do so by lifting rod 43 on pin 45 so 120

125

130

that said pin can pass into the longitudinal portion of elbow slot 44. Spring 65 will at once move arm 55 against stop 68, as in Fig. 1, releasing the printing instrumentalities for further printing, and when pin 23 passes on out of engagement with lever 38, the gravity of said lever and of rod 43 will restore said lever and rod into the position shown in Fig. 1. The time of action of said 10 bell-striking and machine-lock devices may be adjusted either by changing the angular position of pin 23 on drum 6 or by changing the angular position of pin 26 on said drum, but ordinarily the position of pin 23 will be 15 changed for this purpose.

Provision as follows is made for giving one or more visual signals, for notifying the operator of the arrival of his sheet into predetermined sheet-positions: Pointer or stationary index 73, attached to platen-frame 3, has the form of a shield-pointer that conceals a portion of the drum-periphery from the operator. Upon said periphery in any angular position desired I place one or more 20 wax-like colored adhesive wafers, such as the ones shown in Fig. 1 at 6^b and 6^c. Wafers such as these are readily placed in position and readily removed and are inexpensive and can be used for a variety of purposes 25 with the least loss of time. In the drawings wafer 6^b is represented as having a different shape from wafer 6^c, and also a different color, so as to be distinguishable therefrom, in order that one may be used for one 30 purpose and the other for another. The form, substance, color and method of applying the signaling agent are not material, the central requirement being merely that one portion of the drum-periphery should be 35 visually differentiated from the remainder. At the predetermined time the signaling agent, whatever it be, is brought into view from behind pointer or index 73, thereby informing the operator of the position of 40 his sheet.

It will be noted that the pressure of the feed-rolls can be somewhat eased without rocking shaft 14 sufficiently to throw the toothed wheels out of mesh, as in straightening 45 the sheet, depending upon the depth of the teeth on the said wheels and the proportions of the several levers involved. It will be noted also that pin 23 can be moved backwardly past lever 38, bail 42 separating from arm 50 in such an action.

The embodiment of my invention illustrated in Figs. 6 and 7 illustrate an arrangement of gearing in which the toothed wheels operate within the contour of the 50 drum. It is described thus: Platen 5, platen-head 75 and platen arbor 4 are attached to rotate in unison, as usual. Arbor 4 has journalled thereon adjacent to the platen-head the independently revoluble 55 drum 6^a, which is supplied with the same

severed friction-ring 20, spring 25 and split post 19 as before. A partition-wall 76 is conveniently employed to shut off the spring and friction-ring from the remaining mechanism within the drum. The drum is supplied with an internal toothed wheel 31^a between the face-wall thereof and said partition-wall. The face-wall of the drum contains the threaded holes 22 for pin 23 as previously described, and the threaded holes 24 for pin 26 also as before described. Fixedly attached upon platen arbor 4, conveniently by means of set-screw 18^b, is toothed driver 18^a. Laterally extending pin 14^a on platen-frame 3 has journalled thereon a rocking-piece 32^a, and also but independently of said rocking-piece a toothed wheel 34^a, said wheel meshing with toothed driver 18^a aforesaid. A pin 33^a on said rocking-piece has journalled thereon a toothed wheel 35^a, said wheel meshing with wheel 34^a and in some positions of the rocking-piece meshing also with internal gear 31^a on the drum. Said rocking-piece is connected with the controlling sheet-positioning mechanism by means of a rod 32^b one end of which is journalled on a pin 32^c on the rocking-piece and the other end of which contains a short slot 32^d sliding over a pin 32^e on roll-release lever 28 previously described. Said rod has a bend or off-set therein as a convenient means of providing for the clearance of pins 23 and 26, and an upstanding portion of the rod tends to be held against a laterally extending pin 5^a on platen-frame 3^a by an attached spring 12^a, the other end of the spring being attached to a laterally extending post 13^a on platen-frame 3. That is to say, the spring tends to hold toothed wheel 35^a in mesh with toothed wheel 31^a through the intermediate parts described, and pin 5^a prevents the wheels from being crowded together by said spring. The remaining parts are as have been previously described.

The mechanism operates as follows: The feed-roll release lever 28 is pressed rearwardly away from the platen, rocking shaft 14, and through the action of arms 17 on arms 9 easing the pressure of the feed-rolls upon the platen. Further movement of said lever rearwardly brings pin 32^e to the end of slot 32^d and rod 32^b is moved by the said pin against the action of spring 12^a, thereby causing rock-piece 32^a to rock upon pin 14^a and wheel 35^a to be lifted out of mesh with wheel 31^a. Drum 6^a is thereupon rotated backwardly by spring 25 until projection 26 is stopped by stop 25'. Meanwhile paper-gages 16 have been raised into the paper-path by said lever 28. The sheet is now positioned against paper-gages 16, as previously described, and the feed-roll release lever released. Feed-rolls 11 now press the sheet against the platen, which is the principal feed-roll, rod 32^b is moved by spring 12^a

12^a until the upstanding portion thereof rests against pin or post 5^a, rocking-piece 32^a is rocked on pin 14^a, and toothed wheel 35^a is thereby caused to mesh with wheel 31^a, as shown in Fig. 6. The action of the drum and of the various indicating means called into operation through the drum will be identical with that of the mechanism shown in Figs. 1 to 3 from this point, the drum 10 and the sheet moving coördinately in predetermined relationship as before, and the same indices, audible signaling means, visual signaling means, and machine-lock means being employed.

15 It will be noted that the machine-lock means can be released for further printing in the case of both of the embodiments described, either by lifting rod 43, as described, or by moving roll-release lever rearwardly so as to release the actuating mechanism for the drum, thereby permitting spring 25 to rotate the drum backwardly into first position, or by rotating the platen forwardly until pin 23 clears lever 38 and 20 then backwardly into the desired position.

The devices shown in the drawings and described herein are part of a series of closely related inventions or improvements which are presented in a number of co-pending 30 applications for Letters Patent filed by me. The said devices have a number of general objects in common with those forming the subject-matter of different applications in the said series, and to a certain extent embody and utilize various principles and features which are common to devices shown and described in one or another of the said applications. Some of the said common principles and features are claimed 35 broadly in Letters Patent No. 1,087,045, granted upon my application filed April 30, 1909, aforesaid, and in Letters Patent No. 1,053,928, granted February 18, 1913, upon my applications filed April 9, 1912, Serial 40 No. 689,560. The branch of the general invention that is covered hereby is distinguished by the characteristic features specified in the following claims.

I claim as new and desire to secure by Letters Patent,—

1. In a typewriting machine, in combination, a feed-roll-release lever, a platen, a revolute member operated by the platen under the control of said feed-roll-release 55 lever, means under the control of said feed-roll-release lever for giving said member a constant starting position, and indicating means called into operation through said revolute member.

60 2. In a typewriting machine, in combination, an operative member, indicating means called into operation through said member, means for giving said member a constant starting position, paper-gages and the operating devices therefor, a platen, and means

under the control of said paper-gage-operating devices for giving said operative member movement coördinate with that of the platen from the said starting position.

3. In a typewriting machine, in combination, an index-carrier and indices, means for giving said carrier a constant starting position, paper-gages and the operating devices therefor, a platen, and means under the control of said paper-gage-operating devices for giving said index-carrier movement coördinate with that of the platen from the said starting position. 70 75

4. In a typewriting machine, in combination, an operative member, an audible signaling means called into operation through said member, means for giving said member a constant starting position, devices for positioning the leading end of the sheet, a platen, and means for giving said operative member movement coördinate with that of the platen from the said starting position, under the control of said sheet-positioning devices. 80 85

5. In combination, an operative member, a visual signaling means called into operation through said member, means for giving said member a constant starting position, typewriter-mechanism including a platen, and means under the control of a typewriter-mechanism part for giving said member movement simultaneous with that of the platen from the said starting position. 90 95

6. In a typewriting machine, in combination, an operative member, a visual signaling means called into operation through said member, means for giving said member a constant starting position, paper-gages and the operating devices therefor, a platen, and means under the control of said paper-gage-operating devices for giving said operative member movement coördinate with that of the platen from the said starting position. 100 105

7. In combination, typewriter mechanism including a platen and devices for positioning the sheet line-space direction, an operative member, means called into operation through said member for rendering a part or parts of said typewriter mechanism inoperative for use, means for giving said member a constant starting position, and means for giving said member movement coördinate with that of the platen from the said starting position, under the control of 110 115 120 said sheet-positioning devices.

8. In a typewriting machine, in combination, printing instrumentalities, an operative member, means called into operation through said member for locking said printing instrumentalities against use, means for giving said member a constant starting position, paper-gages and the operating devices therefor, a platen, and means under the control of said paper-gage-operating devices 125 130

- for giving said operative member movement coördinate with that of the platen from the said starting position.
9. In combination, typewriter mechanism including a platen, an operative member revoluble about the platen axis, indicating means called into operation through said member, means for giving said member a constant starting position, toothed wheels one thereof rotating in unison with the platen and one thereof rotating in unison with said member, and means under the control of a typewriter-mechanism part for connecting said member to be operated through said toothed wheels.
10. In a typewriting machine, in combination, an operative member, indicating means called into operation through said member, means for giving said member a constant starting position, paper-gage-operating devices, a platen, and actuating means including toothed gearing on said operative member, said gearing connected to give said member movement coördinate with that of the platen under the control of said paper-gage-operating devices.
11. In a typewriting machine, in combination, a feed-roll-release lever, a platen, a toothed wheel revolving in unison with the platen, an operative member movable about the platen axis and having teeth in connection therewith, means for giving said member a constant starting position, indicating means called into operation through said member, and means under the control of said feed-roll-release lever for causing said member to be operated by said toothed wheel through said teeth.
12. In combination, typewriter mechanism including a platen, an index-carrier and indices revoluble about the platen axis, means for giving said carrier a constant starting position, toothed wheels one thereof rotating in unison with the platen and one thereof rotating in unison with said carrier, and means under the control of a typewriter-mechanism part for connecting said carrier to be operated through said toothed wheels.
13. In a typewriting machine, in combination, feed-roll-release devices for positioning the sheet, a platen, an index-carrier revoluble about the platen axis, means for giving said carrier a constant starting position, toothed wheels one thereof rotating in unison with the platen and one thereof rotating in unison with said carrier, and means under the control of said feed-roll-release devices for connecting said member to be operated through said toothed wheels.
14. In combination, typewriter mechanism including a platen, an operative member movable about the platen axis, an audible signaling means called into operation through said member, means for giving said member a constant starting position, toothed wheels one thereof rotating in unison with the platen and one thereof rotating in unison with said member, and means under the control of a typewriter-mechanism part for connecting said member to be operated through said toothed wheels.
15. In a typewriting machine, in combination, paper-gage-operating devices, an operative member, a bell-striking means called into operation through said member, means for giving said member a constant starting position, toothed wheels one thereof rotating in unison with the platen and one thereof rotating in unison with said operative member, and means under the control of said paper-gage-operating devices for connecting said member to be operated through said toothed wheels.
16. In combination, typewriter mechanism including a platen, an operative member spring-returned into initial position, indicating means called into operation through said member, and means under the control of a typewriter-mechanism part for giving said member simultaneous movement with the platen from the said initial position.
17. In combination, typewriter mechanism including a platen, an operative member, indicating means called into operation through said member, spring and stop devices for giving said member a constant starting position, and means under the control of a typewriter-mechanism part for giving said member movement coördinate with that of the platen from the said starting position.
18. In combination, typewriter mechanism including a platen, an independently-revoluble member normally connected with the platen, indicating means called into operation through said member, means under the control of a typewriter-mechanism part for disconnecting said member from the platen, and means acting to return said disconnected member into initial position.
19. In combination, typewriter mechanism including a platen, an operative member, indicating means called into operation through said member, means for giving said member a constant starting position, and toothed wheels normally in mesh but separable under the control of a typewriter-mechanism part for giving said member movement coördinate with that of the platen from the said starting position.
20. In a typewriting machine, in combination, paper-gage-operating devices, a platen, an operative member, indicating means called into operation through said member, toothed wheels normally in mesh but separable under the control of said paper-gage-operating devices, and means rendered effective by the separation of said toothed wheels to return said member into initial position.

21. In combination, typewriter mechanism including a platen, an operative member spring-returned into starting position, indicating means called into operation through 5 said member, and toothed gearing under the control of a typewriter-mechanism part for giving said member simultaneous movement with the platen from the said starting position.
- 10 22. In combination, typewriter mechanism including a platen, an operative member, indicating means called into operation through said member, means including a spring and co-operating stop for giving said member a 15 constant starting position, and toothed gearing connected under the control of a typewriter-mechanism part for giving said mem-
- ber simultaneous movement with the platen from the said starting position.
23. In a typewriting machine, in combination, devices for positioning the leading end of the sheet, a platen, an operative member, indicating means called into operation through said member, means for giving said member a constant starting position, and 20 toothed wheels between said member and the platen, said wheels connected under the control of said sheet-positioning devices. 25

In testimony whereof I affix my signature in presence of two witnesses.

WILLIAM J. NEIDIG.

Witnesses:

JOHN K. BONNELL,
FRANCES M. BONNELL.
